UNITED STATES PATENT OFFICE

JUSTIN K. BABCOCK, OF CLEVELAND, OHIO

COUPLING

Application filed August 28, 1931. Serial No. 560,009.

This invention relates to couplings, particularly to those designed for lifting purposes, one of the objects being to improve the construction of such couplings so that they may be easily coupled and uncoupled and at the same time be simple and sturdy. Other objects may later become apparent.

The invention is characterized by the use of a frame constructed with a slot for the reception and engagement of a link, a plate being positioned and arranged behind this slot so that when the link is lowered it will ride out on this plate and be automatically disengaged. It is particularly advantageous when used in connection with a crane, as the operator thereof may couple and uncouple the lifting cable from objects which are to be lifted by sidewise and vertical manipulation of the cable, thus obviating the need of a helper on the floor.

In the drawing:

Figure 1 is a side view of an example of this invention as it appears in use.

Figure 2 is a vertical cross-section on the line II—II of Figure 1.

Figure 3 is a horizontal cross-section on the line III—III of Figure 1.

Having reference to this drawing, a tank 2 containing liquid is to be used in pickling coils of metal rods 3 carried on the hanger apparatus 4. The coupling forming the subject of this invention is shown fixed to this hanger for the purpose of facilitating its movement into and out of the tank. This coupling comprises a semi-cylindrically ended straight-sided frame 5 constructed with a slot 6 beginning in its top end and continuing down one side in enlarged proportions. A flat plate 7 is fixed to the bottom part of this slot and is inclined from there up to the inner wall of the opposite side of the frame, this plate preferably being welded in place.

A tubular cross-bar of the hanger 4 passes through the frame 5 beneath the plate 7 and is bolted in position, both side ends of the frame 5 being open. A link comprising a shank 8 and enlarged end 9 is shown engaged in the top of the frame 5 and affixed to a lifting cable 10.

The coupling is now in lifting position,

and it may be observed that, because of the simplicity and size of the parts, there is little danger of breakage under lifting strains or of disengagement.

The enlarged end 9 is shown in rounded form so that the frame 5 fixed to the hanger 4 may be rotated if desired, this end being constructed with flat sides when it is necessary to hold the hanger against rotation. When the crane operator desires to release the coupling he merely releases the tension on the cable 10, allowing the link to fall so that its enlarged end 9 rides along the plate 7 and out of the slot 6, as indicated by dotted lines in Figure 2, this action being reversed when he desires to recouple.

A specific example of this invention is shown in compliance with the patent statutes, and not with the intention of limiting its scope thereto, except as defined by the appended claim.

I claim:

A coupling comprising, in combination, a frame having semi-cylindrically shaped ends in straight back and forth side walls, one of said side walls being provided with a slot which extends from its upper end downwardly in enlarged proportions, a flat deflector plate extending from the bottom wall of said slot upwardly and rearwardly to the opposite side wall, said plate being welded in position and a link having an enlarged lower end for insertion through the enlarged part of said slot in said frame for engagement with the top thereof.

In testimony whereof, I have hereunto set my hand.

JUSTIN K. BABCOCK.
